UNITED STATES PATENT OFFICE.

RAY TRAUTMAN, OF MINNEAPOLIS, MINNESOTA.

ARTIFICIAL LIMB.

1,326,883.

Specification of Letters Patent.

Patented Dec. 30, 1919.

Application filed December 11, 1918. Serial No. 266,236.

To all whom it may concern:

Be it known that I, RAY TRAUTMAN, a citizen of the United States, residing at Minneapolis, in the county of Hennepin and State of Minnesota, have invented certain new and useful Improvements in Artificial Limbs, of which the following is a specification.

My invention relates to artificial limbs.

10 An object is to provide for the construction of various parts of such limbs of standard size in such manner that the parts may be readily put together to form limbs having any desired circumference and length, according to the particular person who is to be fitted. An object in particular is to construct a fiber shell in such manner that the limbs may be readily made up from shell members of uniform size in accordance with 15 the measurements and requirements of any particular person who is to be provided with an artificial limb. Another object is to provide a strong and durable construction of 20 artificial limbs in which the functions of the natural limb are closely simulated without the use of complicated mechanism liable to 25 get out of order.

The full objects and advantages of my invention will appear in connection with the 30 detailed description thereof and the novel features embodied in my inventive idea will be particularly pointed out in the claim.

In the drawings,—

Figure 1 is a side view showing a thigh, shank and foot member for cases of amputation above the knee. Fig. 2 is an enlarged view in vertical section showing the connection between the knee-block and the shank member. Fig. 3 is a detail at right angles to Fig. 2. Fig. 4 is a view similar to Fig. 2 but showing the parts separated and the knee block in side elevation. Fig. 5 is a view in cross section on the line 5—5 of Fig. 2. Fig. 6 is a view mostly in central vertical section showing the lower portion of the shank member and its attachment to the foot member. Fig. 7 is a section on the line 7—7 of Fig. 6. Fig. 8 is a view in cross section on the line 8—8 of Fig. 6. Fig. 9 is a view similar to Fig. 6 but showing the position assumed by the foot member when the heel strikes the ground in walking. Fig. 10 is a side view showing a thigh, shank and foot member for cases of amputation below the knee. Fig. 11 is a cross section on the line 55 11—11 of Fig. 10. Fig. 12 is a detail showing the inner socket from the rear.

Referring to the construction shown in Figs. 1 to 9, the drawings show a thigh member 14, a shank member 16, and a foot member 18. The members 14 and 16 are shells formed of fiber molded into suitable shape of standard size and having the two longitudinal edges brought together at the rear to form an overlapping joint which may be secured with the desired amount of overlapping by rivets or suitable fasteners 20. A block 22 is secured within the lower front portion of the shank member by screws or fasteners 24 so as to leave a space 26 between the rear of the block and the portion of the shell having the overlapping joint. As shown by dotted lines in Fig. 8 the extent to which the joint is overlapped may be varied and the circumference made greater 75 or smaller as may be desired to accommodate different persons. The inherent resiliency of the fiber permits this to be done before the rivets are secured in place without interfering with the position of the block 22 and the attaching means for the foot member 18. As best shown in Figs. 6, 7, and 9 a metal strip 28 is secured inside of the shank member at each side thereof by screws or rivets 30 and the lower ends of these two strips are 85 secured to a sleeve or bushing 32 having a seat upon the lower end of the block 22 by which means the sleeve is firmly held in place. A cylindrical member 34 is rotatably mounted in the sleeve and a rod 36 attached 90 to the cylindrical member extends down through a slot 38 in the sleeve and then through a hole in the foot member into a recess 40 with which the bottom of the foot member is provided. The lower end of the rod 95 36 is screw threaded and is provided with an integral washer 42 and nut 44 to firmly hold the foot member, rockably mounted upon the lower end of the shank member. The lower rear portion of the block 22 is provided with 100 a beveled surface 46 and the adjacent top portion of the foot member is provided with a similar beveled surface 48 diverging from the surface 46. These two beveled surfaces

are provided with holes in alinement with each other for receiving the opposite ends of an elastic member here shown as a coil spring 50. The portion of the foot member 5 adjacent the lower front portion of the block 22 is cut out and provided with a rubber buffer 52 secured in place by one or more screws 54. The coil spring 50 normally holds the foot member in the position shown in Fig. 6 and in walking when the heel strikes the ground the spring is compressed and the foot member moves into the position shown in Fig. 9. When the weight of the wearer is taken off the heel the foot member turns 15 into the position shown in Fig. 6, the buffer 52 cushioning this movement. The rear of the foot member may be dressed down at 56 so as to fit nicely within the lower end of the shank member according to the amount 20 of overlapping of the longitudinal edges thereof. The shank member and the thigh member are secured together by a joint constructed as follows: Knee joint strips 58 are secured to the upper end of the shank member at opposite sides thereof by rivets 25 or other suitable fasteners. A knee block 60 has a reduced upper portion 62 which fits into the lower end of the thigh member and is secured thereto by screws or other suitable 30 fasteners 64. A rod 66 passes through a hole in the knee block and the ends of this rod pass through holes in the enlarged upper ends 70 of the knee straps whereby the shank member is trunnioned to the knee 35 block. The upper end of the shank member may be cut off as indicated by dotted lines "a" in Fig. 4, according to the length desirable for the particular person, and for the same purpose the lower end of the thigh 40 member may be cut off, as desired, in a manner indicated by the dotted lines "b." The knee straps may be secured in proper position according to the amount cut off from the shank member, as indicated by dotted 45 lines in Fig. 4. The thigh member 14 may have its longitudinal edges overlapped the proper amount according to the circumference desired by the wearer, and these edges are then secured by rivets 20. The upper 50 end of the thigh member is provided with a circumferential finishing piece of leather 72 which may be overlapped, as shown at 74 to an extent corresponding to the amount of overlapping of the edges of the fiber shell. 55 The upper portion of the knee block may be dressed down the proper amount according to the size determined upon for the thigh member. It is thus apparent that these shell members of standard size may be kept in 60 stock and that all parts of the artificial limb may be readily assembled so as to provide the length and circumference which is suitable for any particular person. A foot member 65 of any desired size can, of course, be readily attached to the lower end of the

shank member in the manner previously described.

In order to control the movement of the shank member the following construction is provided. A bar 76 is secured by a pivot 70 pin 78 within a slot in the rear portion of the knee block. This bar extends down inside the shank member and an elastic strip 80 is secured at its middle to the lower end of said bar and the ends of the elastic strip 75 are secured in suitable manner, as by cords 82 to the upper end of the shank member. When the limb is bent at the knee in walking the elastic member will be stretched and when the foot is lifted from the ground the shank member will be automatically brought forward into alinement with the thigh member. A rubber buffer 84 may be placed on the rear of the lower end of the bar 76 in order to cushion shocks. The thigh member 80 with its attached parts is held to the wearer by the customary suspenders 85.

The previous description relates to artificial limbs for cases of amputation above the knee. My invention, however, is not limited 90 to limbs of this character, but may be employed in other cases. For instance, Figs. 10, 11 and 12 illustrate how the adjustable or variable features previously described may be applied to artificial limbs for cases 95 of amputation below the knee. In the construction shown in these latter figures the lower knee straps 58 are pivotally connected to upper knee straps 86, the upper ends of which are secured to a lacer 88, the latter 100 being connected at the rear with the shank member by a check strap 90. In artificial limbs of this character inner sockets are usually employed. In order that the inner 105 socket 92 which I employ may be adjusted according to the desired circumference I provide this socket with a vertical opening at the rear secured by a lacing 94 by means of which the socket may be adjusted. The shank member may then be adjusted to fit 110 the socket. The length of the shank may be reduced as previously described in order to make it suitable for various persons.

The operation and advantages of my invention will be readily understood from the 115 foregoing description. Fiber shell members for artificial limbs may be constructed of uniform size and limbs may be quickly assembled having any desired dimension both circumferentially and longitudinally according to the measurement of the particular person. This does away with the carrying of various sizes in stock and renders the fitting of various persons with artificial limbs an extremely easy matter with the assurance 120 that the circumference and size of the limb will be just what is required.

I claim:

An artificial limb comprising a hollow shell of resilient material, said shell having 130

longitudinal edges adapted to be overlapped for a greater or less extent, a separate block secured within one end of said shell and normally spaced sufficiently from the side there-
5 of having said longitudinal edges to permit the maximum desired amount of overlap-
ping of said longitudinal edges, whereby

said shell may be constructed of standard size and subsequently given the particular circumference desired, and limb attaching 10 means supported by said block.

In testimony whereof I hereunto affix my signature.

RAY TRAUTMAN.
